HINGE-MOUNTED UMBRELLA HOLDER

William S. Spangle, 627 Orchard Hill Drive,
Pittsburgh, Pa.

Filed Oct. 14, 1963, Ser. No. 76,965

Term of patent 7 years

(Cl. D33—17)

Fig. 1.

Fig. 2.

Fig. 3.

Fig. 4.

FIG. 1 is a side, elevational view of a hinge mounted umbrella holder, showing my new design;

FIG. 2 is a vertical, cross-sectional view of the umbrella holder;

FIG. 3 is a top, perspective view of said umbrella holder; and

FIG. 4 is a side elevational view on a reduced scale, the dotted lines therein being shown for illustrative purposes only.

I claim:

The ornamental design for a hinge-mounted umbrella holder, as shown and described.
